(57) **CLAIM**

The ornamental design for a cigar holder, as shown and described.

DESCRIPTION

FIG. 1 is a rear view of the cigar holder showing my new design;

FIG. 2 is a front view thereof;

FIG. 3 is a top view thereof;

FIG. 4 is a bottom view thereof;

FIG. 5 is a left side view thereof;

FIG. 6 is a right side view thereof; and,

FIG. 7 is a perspective view thereof.

The broken lines illustrate environmental subject matter only that forms no part of the claimed design.
